SLIPPER

Gustav Cohn, New York, N. Y.

Application December 22, 1950, Serial No. 13,548

Term of patent 3½ years

(Cl. D7—7)

To all whom it may concern:

Be it known that I, Gustav Cohn, a citizen of the United States, residing in the Borough of Manhattan, city and State of New York, have invented a new, original, and ornamental Design for a Slipper, of which the following is a specification, reference being had to the accompanying drawing, forming part thereof, in which the drawing illustrates as follows:

Fig. 1 is a side elevational view of a slipper showing my new design; and

Fig. 2 is a top plan view thereof.

I claim:

The ornamental design for a slipper, substantially as shown.

GUSTAV COHN.
